UNITED STATES PATENT OFFICE.

RICHARD P. COLLINS, OF NORWOOD, PENNSYLVANIA.

MEANS FOR ATTACHING FLUE PIPES IN CHIMNEYS.

Application filed October 4, 1926. Serial No. 139,510.

This invention relates to means for attaching flue pipes in chimneys.

An object of my invention is to provide means wherein the connection between the flue pipes and a chimney may be made without the use of mortar or the like and whereby the pipes may be disconnected and connected with a minimum of labor and expense.

10 Another object is to construct a chimney with means which are so formed as to provide for various flue connections from furnaces and heaters.

Another object is to provide adjustable means for attaching flue pipes in a chimney, such adjustment providing for or accommodating a plurality of angles at which a flue pipe may enter a chimney.

Another object is to provide means for attaching flue pipes in a chimney with a clean-out opening having a closure element so formed with locking means as to be effective in either of the positions of the flue pipe attaching means.

25 Another object is to produce an efficient, strong and durable means for attaching flue pipes in chimneys which may be economically constructed and operated.

Other objects and advantages will herein-
30 after appear.

The views of the drawings are:

Figure 1 is a front elevation of one embodiment of my invention;

Figure 2 is a section on the line 2—2 of

35 Figure 1;

Prior to my invention, it has been customary in connecting the flue pipe or pipes, extending from furnaces or heaters into a chimney, to pass the said pipes into suitably formed openings in a chimney and to secure them in place by cement. The flue pipes are in most instances removed during the summer months, and require periodic cleaning, and it is necessary, when the pipes are removed for storing or for cleaning, to break out the cement work.

40 By the present invention, I provide simple and effective means whereby the connection between the flue pipes and a chimney may be made without the use of mortar or the like and whereby the pipes may be disconnected and connected with a minimum of labor and expense.

45 For further facilitating the connection, I provide means for accommodating various different angular relations between the flue

pipe and the vertical face of the plate or chimney.

With reference to the drawings, the device in one form may comprise a metal plate 1 having a main opening 2 for the flue pipe of a furnace and having a second opening 3 for a second flue pipe, such for example as that extending from a water heater or the like; and having in addition two openings 4, 4, at the respective ends which function, as hereinafter described, as cleaning ports.

Although a single cleaning port is in some instances all that is required, I have provided two in the present instance in order to 70 make the plate reversible for the purpose of arranging the openings 2 and 3 in the desired relative positions. Since the ports 4, 4, are normally closed, I provide each with a door 5 hinged in the present instance to 75 the plate, as indicated at 6, each door having a latch 7 adapted to cooperate with one of a pair of suitably notched lugs 8, 8, on the face of the plate 1 to retain the door in the closed position, as clearly illustrated. 80

The latches 7 are pivotally secured to the doors at 9, and a handle element 10 is attached to the outer end of each of the latch elements 7 by means preferably of a flexible connector such as a chain or link 11 whereby 85 the latch 7 may be manipulated to open or close the door 5. Since the plate is adapted to be used in either one of two upright positions, I provide in each case a pair of oppositely arranged lugs 8, 8, symmetrically arranged with respect to the latch 7 so that the latter may co-operate with either one or the other, depending upon the position of the plate 1.

Since it is not always desirable to employ 90 the flue opening 3 intended primarily for a hot water heater or the like, I provide the latter with a suitable closure 12, this being in the form, in the present instance, of a substantially circular plate having side extensions 13, 13, adapted to rest on suitable notched lugs 14, 14, on the plate 1, as clearly illustrated in Fig. 1, whereby the plate 12 is supported in position. When the opening 3 is not in use, it is ordinarily immaterial 100 whether the plate 1 occupies the position illustrated or the reverse position, wherefore I provide means for supporting the closure 12 in but one position of the plate. Where the port 3 is used, however, the cover 12 105 must be removed, and the plate may be adjusted to either of the alternative positions.

It is not always convenient to extend the flue pipe into the opening 2 of the plate 1 at any given angle to the latter, and I therefore provide means for receiving the flue pipe in any one of a number of different angular positions. This adjustable means comprises a pair of sleeves 15 and 16, the sleeve 15 being secured in the plate 1, as clearly shown in Fig. 2, so as to be capable 5 of rotational movement therein. This adjustable connection between the sleeve 15 and the plate 1 is accomplished in the present instance by means of clamps 17 which engage the inner flanged edge 18 of the sleeve 15, there being preferably three or more of these clamping elements so that the sleeve 15 is retained firmly in position. As illustrated in Fig. 2, the plane of the forward face of the sleeve 15 is formed at an angle 15 to the plane of the rear face so that by rotating the sleeve, the angular relation between the plane of the forward face of the sleeve and that of the plate 1 may be varied. The sleeve 16 also is so formed that 20 the plane of one end face is angularly arranged with respect to that of the other end face, and this sleeve 16 is secured on the outer end of the sleeve 15 so as to provide for relative rotation between these sleeves. 25 Clamps 19 are employed in the present instance for adjustably retaining the sleeve 16 on the sleeve 15, and preferably there are three or more of these clamps in order to form a firm connection between the parts. 30 By rotating the sleeve 15 in the plate 1, and by further rotating the sleeve 16 with respect to the sleeve 15, the angular relation 35 between the outer face of the sleeve 16, which receives the flue pipe, and the plate 1 may 40 be varied as desired.

It will be noted that in the present instance a flange 20 is formed on the inside of the plate 1 which fits within the opening in the chimney in which the plate 1 is adapted 45 to be secured, and any suitable means such as bolts or clamps (not shown) may be used to retain the plate in position. The plate preferably is detachably secured in

the chimney, although it may be permanently fixed if desired. 50

Obviously there may be many variations and modifications in the device as herein described. The same angle adjusting device may be applied to the opening 3 for example and the arrangement of flue openings 55 and cleaning ports may vary largely in accordance with the particular needs.

I claim:

1. Means for attaching a flue pipe in a chimney comprising a plate adapted to be secured in an opening in the chimney, said plate having an opening for the reception of a flue, clean-out openings at the respective ends of the plate and on opposite sides of said flue opening, a closure element for each of said clean-out openings, and locking means for said closures effective in either one of the two alternate positions of the plate and the one in which the respective clean-out openings are respectively at top 70 and bottom.

2. Means for attaching flue pipes in chimneys comprising a reversible plate adapted to be secured in an opening in the chimney, said plate having at least one flue opening, 75 said plate also having a clean-out port at each end thereof, doors hinged to the plate and constituting closures for the said clean-out ports, a latch pivotally secured to each of said doors, and notched lugs on the plate adapted to cooperate with the respective latches to lock the doors, when the plate is in either position.

3. Means for attaching flue pipes in a chimney comprising a reversible plate adapted to be secured in an opening in the chimney in either one of two alternate positions, said plate having clean-out openings arranged one above the other with means disposed between said openings for adjustably receiving a flue, closures pivoted to the plate and adapted to cover the said openings, and means for latching the closures when the plate is in either of its alternate positions. 90

RICHARD P. COLLINS.
